ATTORNEYS.

UNITED STATES PATENT OFFICE.

JOSEPH J. DUNNE, OF SEATTLE, WASHINGTON.

VALVE.

Application filed July 13, 1923. Serial No. 651,390.

To all whom it may concern.

Be it known that I, JOSEPH J. DUNNE, a citizen of the United States, and a resident of Seattle, county of King, State of Washington, have invented a new and useful Valve, of which the following is a specification.

The present invention relates to improvements in valves and has particular reference to a valve adapted to be closed by screw action. It is proposed to provide an improvement on a valve of this character which will allow the valve to be closed instantly without executing a number of turns which would otherwise be necessary for the closing of the valve. It is further proposed to provide means allowing this feature of quick action to be eliminated at the desire of the operator, in which case the valve operates like any common valve now on the market. Further objects and advantages of my device will appear as the specification proceeds.

The preferred form of my invention is illustrated in the accompanying drawing in which Figure 1 shows a vertical section through my valve, Figure 2 a detail view in side elevation of a valve head arrangement, Figure 3 a longitudinal section through the said arrangement, Figures 4 and 5 transverse sections taken along line 4-5 of Figure 1 with the valve stem shown in different positions relative to the valve head, Figure 6 a perspective detail view illustrating the engagement between the valve stem and the valve head, Figure 7 a side view of the valve head showing the same in its relation to the valve stem when my quick closing feature has been used, Figure 8 a perspective detail view of a device for allowing the quick action feature to be eliminated and Figure 9 a transverse section taken along line 9-9 of Figure 1. While I have shown only the preferred form of the invention, it should be understood that various changes or modifications may be made within the scope of the claims hereto attached without departing from the spirit of the invention.

In its preferred form, my device com-

prises a valve housing (1) adapted to threadedly engage adjoining pipes by means of its internal threads (2) and (3) so as to allow a liquid to pass therethrough. An internal wall (4) is bent to provide an axial seat (6) for the valve (7). The latter comprises a valve stem (8), having a suitable handle (9) thereon by means of which it may be turned and the valve head (11). The valve stem has an enlarged threaded portion (12) adapted to engage the member (13) extending radially from the valve housing and secured thereto by means of the threaded engagement shown at (14). A recess (16) in said member allows a packing (17) to be introduced which is forced upon the stem and the walls of the recess by means of a gland (18) and the cap (19).

It will be seen that if the handle (9) is turned, the valve stem moves upwardly or downwardly respectively and imparts its motion to the valve head (11) previously referred to. This valve head consists of three principal parts, that is, the sleeve (21), the gland (22) and the seat engaging member (23). The sleeve (21) is adapted to slidably engage the lower reduced end (24) of the stem. It has an enlarged base (26) fitting into an annular flange (27) extending upwardly from the valve seat engaging member and held in position by the gland (22) which is threaded into the flange (27). The base of the sleeve (21) is stepped as shown at (28) to provide a seat for the spring (29) which bears with its upper end against the enlarged threaded portion (22) of the stem. A small stud (31) extending from the base of the sleeve (21) in the seat engaging member (23) prevents rotary motion of the sleeve relative to the latter member. The reduced end (24) of the stem is provided with a transverse pin (32) extending in the peripheral groove (33) in the sleeve (21) and adapted to register with longitudinal grooves (34) in the sleeve when the latter occupies a predetermined position relative to the stem. When the pin registers with the longitudinal grooves, the spring (29) forces the

sleeve downwardly. Normally, however, the pin rests in the peripheral grooves and forces the sleeve (21) and with it the whole valve head to follow the motions of the 5 valve stem.

As will be seen particularly well from Figures 2 and 7, the gland (22) has extending from its upper face two lugs (36), each lug being formed to provide a gradual 10 ascent (37) on one side and a steep face (38) on the other side. These lugs are adapted to engage with a pin (39) supported in the member (13) with freedom of longitudinal motion and normally depressed 15 by a spring (41) but adapted to yield to upward pressure. The pin (39) extends in the path of the two lugs (36) and is lifted out of the way when the valve stem and the valve head rotate counter-clockwise by 20 ascending the gradual ascent (37), passing over the crest and dropping down the vertical side of the lug, while it stops rotary motion of the valve head in a clockwise direction by directly engaging with the vertical side of the lug. The pin (39) may be 25 lifted so as to clear the lugs (36) all together and to thereby become inoperative by means of the crankpin (42) adapted to be actuated by rotating the handle (43). 30 The operation of my valve head may be described as follows: To open the valve, the handle (9) is turned to the left, as viewed from above. This causes the pin (32) which in the beginning occupies the position shown in Figure 5, to enter the peripheral grooves (33) as shown in Figure 4, and after it has reached the end of the grooves it causes the sleeve (21) and thereby the 35 valve head as a whole to follow the rotary and ascending motion of the stem (8). After several turns have been made, the lugs (36) extending upwardly from the gland (22) engage with the pin (39). But since the engagement takes place at the slowly 40 ascending side of the lugs, the pin (39) merely rides over the lugs and does not perform any function. When the valve is fully opened and it is desired to close the same quickly, the handle (9) is turned to the right. The clockwise motion of the stem (8) would normally cause the valve head to turn clockwise too, but as soon as the first 45 one of the lugs (36) comes in contact with the pin (39) it is prevented from rotating any further. Since the rotary motion of the stem is not affected by the stop, it continues until the pin 32 registers with the longitudinal slots (34) in the sleeve (21), when the spring (29) becomes active and 50 forces the sleeve (21) and the whole valve head upon its seat with a quick straight longitudinal motion. Although the valve is now seated and stops the flow of liquid, the operator may continue his turning motion 55 which will cause the pin (32) to slowly de-

scend in the longitudinal slot (34) and to return to its original position indicated in Figure 5, while at the same time, the spring (29) is placed under tension again.

If it is desired to eliminate the feature 70 causing the valve head to descend directly, the stop pin (39) may be raised by turning the crank pin (42) and it will then be sufficiently high to never touch the lugs (36).

I claim:

1. A valve of the character described adapted to be actuated by screw action, having means associated therewith for imparting straight longitudinal motion to the same for effecting a rapid action of the valve, in 80 combination with means for rendering the former means active during the initial screw action in a downward direction.

2. A valve of the character described comprising a stem adapted to be actuated by 85 screw action, a valve head slidable thereon, spring means tending to impart endwise motion to the valve head relative to the stem, means normally preventing such motion and means for rendering the latter means inactive at predetermined times.

3. A valve of the character described comprising a stem adapted to be actuated by screw action, a valve head slidable thereon, spring means tending to impart endwise 95 motion to the valve head relative to the stem, a pin extending from the stem into a transverse groove in the valve head normally preventing such motion and means for causing said pin to register with a longitudinal groove at predetermined times 100 allowing the head to yield to the spring action.

4. A valve of the character described comprising a stem adapted to be actuated by 105 screw action, a valve head slidable thereon, spring means tending to impart endwise motion to the valve head relative to the stem, a pin extending from the stem into a transverse groove in the valve head normally preventing such motion and means for causing said pin to register with a longitudinal groove at predetermined times 110 allowing the head to yield to the spring action, comprising a stop temporarily preventing the valve head from rotating with the stem.

5. A valve of the character described comprising a stem adapted to be actuated by 120 screw action, a valve head slidable thereon having a lug rising therefrom, spring means tending to impart endwise motion to the valve head relative to the stem, a pin extending from the stem into a transverse 125 groove in the valve head normally preventing such motion, and a stop in the path of the lug allowing the latter to pass on in one direction only so as to prevent the valve head from rotating with the stem in the other direction, whereby the pin is caused 130

to register with a longitudinal groove which allows the valve head to yield to the spring action.

6. In a valve of the character described, a valve stem adapted to be turned, having a valve head thereon and means for preventing rotary motion of the head with the stem in

one direction, comprising a lug rising from the valve head and an axially yielding stop extending into the path of the lug, the latter being formed to lift the stop when moving in one direction and to be held by the stop when moving in the opposite direction.

JOSEPH J. DUNNE.
